UNITED STATES PATENT OFFICE.

PEDER PEDERSON WESTBYE, OF PETERBOROUGH, ONTARIO, CANADA.

BARKING DRUM.

Application filed December 30, 1926, Serial No. 158,106, and in Canada October 11, 1926.

This invention relates to apparatus employed in removing the bark from pulp wood, and particularly to barking drums now generally in use for that purpose.

5 In this process a large quantity of logs is fed into a long drum or series of drums, which on being rotated cause the logs to rub together and grind off the bark. Water is supplied to wash the ground bark from the 10 logs and out of the drum through slots in its walls.

Owing to the great weight of the logs and the severe impacts of the tumbling logs, the drums require to be built very strong and 15 with as few weak points as possible.

The object of my invention is to provide an improved and simple form of construction, having the maximum of strength and resistance to withstand the violent stresses 20 that are generated during operation.

A further object is to provide a barking drum with means to remove readily the tires and gears or other mechanism used to produce the necessary rotation.

25 A further object is to provide a barking drum having an improved form of connection between the sectional drums.

My invention consists briefly in a series of 30 rings with inwardly projecting teeth, to which channel bars are fitted over the crowns of the teeth, and riveted directly thereto, forming a slotted cylinder having a practically smooth interior surface of the character required. To this cylinder by means 35 of the rings, the driving and running mechanism is detachably secured.

When two or more sectional drums are installed, to form one apparatus, a special sleeve covers the edges of the adjacent end 40 plates.

The following is a description of one form in which my invention may be carried out, reference being made to the accompanying drawings in which:—

45 Fig. 1. is a cross section of a ring on the line 1—1 of Fig. 2.

Fig. 2. is a plan view of a portion of a ring from outside.

50 Fig. 3. is a cross section of a ring on the line 3—3 of Fig. 2.

Fig. 4. is a cross section of a ring with a tire mounted thereon.

Fig. 5. is a side view of the same partially in section.

55 Fig. 6. is a cross section of a ring with a gear mounted thereon.

Fig. 7. is a side view of the same partially in section.

Fig. 8. is a side view of a barking drum constructed with the improved features of 60 my invention, showing in section the sleeve covering the end plate.

In the drum shown in Fig. 8, the ring 1, surrounding the bars 2, are formed with inwardly projecting teeth 10, with a continuous mid rib 11. These rings are preferably 65 steel castings.

The rings 1, may have indentations 10, inwardly projecting therein, with a continuous midrib 11, as shown in Figures 2 and 3. 70

As shown in Fig. 3, the channel bars 2, fit over the top of the teeth 10, with their flanges 20, fitting to the sides of the teeth 10. A series of rivets 3, on each side of the midrib 11, short and with heads countersunk, 75 provide a very secure attachment between the rings 1, and the channel bars 2.

To provide for the support of the tires 4, or the gears 5, the rings 1, have outwardly projecting flanges 12, to which the inwardly 80 projecting flanges 41, of the tire 4, and the flange 51, of the gear 5, are secured by a series of bolts 6.

In the drum as shown in Fig. 8, each channel bar 2, is riveted to five rings spaced 85 apart, and to the end plates 7. This arrangement can be varied by the addition or the omission of some of the rings, according to the length of the drums, or the strength 90 of the construction desired.

The teeth of the rings may be solid metal, in place of the partially hollow form shown.

The tires and gears may be secured to the rings by other means, but I prefer to 95 have them readily detachable.

The end plates 7, of each section of a complete barking apparatus, which are adjacent as shown at the right side of Fig. 8, are provided with a sleeve or flanged ring 100 8, covering the inner edges of the plates and riveted to the plate 7, nearest the feed end of the drum.

With this construction, a drum is provided with an inner surface practically 105 smooth, having slots between the adjacent channel bars extending between the rings.

The channel bars fitted over the crowns of the teeth of the rings give a very robust construction to the cylinder.

110 The flanges of the channel bars enclosing the sides of the teeth protect the short

rivets from shearing action and thereby ensure great durability and freedom from repairs.

The attachment of the tires and gears to the rings enable easy and rapid replacement for worn or injured parts.

The sleeve 8, which covers the inner edge of the end plates 7, not only prevents the entrance of wedges of wood jamming in the space between the adjacent end plates, which is liable to cause damage and displacement, but also protects the edges of the plates from damage from the blows of the logs passing through the drum.

15 What I claim is:—

1. A barking drum comprising a series of rings having integral inwardly projecting teeth, with a plurality of channel bars secured over the crowns of the teeth, and adapted to form a longitudinally slotted cylinder.

2. A barking drum comprising a series of rings with integral inwardly projecting broad teeth, with a plurality of channel bars adapted to fit over the crowns of the teeth and rigidly secured thereto, and spaced to provide slots between the sides of the bars.

3. A barking drum comprising a series of rings having integral inwardly projecting teeth, a plurality of channel bars directly supported on the crowns of the teeth and rigidly secured thereto, adapted to form a longitudinally slotted cylinder.

35 4. A barking drum comprising a series of rings with continuous midribs having integral inwardly projecting teeth, a plurality of channel bars directly supported on the crowns of the teeth and rigidly secured thereto, adapted to form a longitudinally slotted cylinder.

5. A barking drum comprising a series of rings with continuous midribs having integral inwardly projecting teeth, a plurality of channel bars directly supported on the crowns of the teeth and rigidly secured thereto by counter sunk rivets, adapted to form a longitudinally slotted cylinder.

6. A barking drum comprising a series of 50 large rings with integral inwardly project-

ing broad teeth, a plurality of shallow channel bars adapted to fit over the crowns of the teeth and rigidly secured thereto, adapted to form a cylinder with a practically smooth interior surface, having narrow longitudinal slots between the sides of the bars.

7. A barking drum comprising a series of large rings with integral inwardly projecting teeth, adapted to be attached outwardly to spur gear rings and racer rings, a plurality of shallow channel bars fitted over the crowns of the teeth and rigidly secured thereto, spaced to provide longitudinal slots between the sides of the adjacent bars.

8. In a barking drum the combination of a plurality of channel bars mounted on integral inwardly projecting indentations in a series of rings, with outer rings removably secured to certain of such indented rings.

9. In a barking drum the combination of a plurality of channel bars mounted on the integral inwardly projecting indentations in a series of rings certain of which have outwardly projecting flanges with outer rings having inwardly projecting flanges and bolts to secure the flanges of each pair of rings.

10. In a barking drum the combination of a series of rings having integral teeth projecting inwardly, with a plurality of channel bars closely fitting over the top and sides of the teeth and riveted directly thereto.

11. A barking drum comprising a series of rings with inwardly projecting indentations and a plurality of channel bars secured on the indentations adapted to form a longitudinally slotted cylinder.

12. An article of manufacture comprising a ring formed with inwardly projecting indentations adapted to support the channel bars of a barking drum.

13. In a barking drum, a series of rings with inwardly projecting indentations and a plurality of channel bars secured to the indentations.

Montreal, 16th November, 1926.
PEDER PEDERSON WESTBYE.
